UNITED STATES PATENT OFFICE.

HARRY C. LEONARD, OF GRAND RAPIDS, MICHIGAN, ASSIGNOR TO GRAND RAPIDS REFRIGERATOR COMPANY, OF GRAND RAPIDS, MICHIGAN, A CORPORATION OF MICHIGAN.

DESIGN FOR A HINGE FOR REFRIGERATORS.

47,000.

Specification for Design.

Patented Feb. 23, 1915.

Application filed September 15, 1914. Serial No. 861,895. Term of patent 7 years.

To all whom it may concern:

Be it known that I, HARRY C. LEONARD, a citizen of the United States, residing at Grand Rapids, in the county of Kent and State of Michigan, have invented a certain new and ornamental Design for a Hinge for Refrigerators, of which the following is a specification, which, taken in connection with the accompanying drawing, fully discloses the design such that others may understand the same.

In the drawing: Figure 1 is an edge view of the hinge. Fig. 2 is a front view thereof; and Fig. 3 is a perspective view showing my design for hinge.

Similar reference characters refer to similar parts throughout the several views of the drawing.

In its essential features the hinge comprises a relatively long hinge member 1 and a shorter hinge member 2 having an angular

inner end 3, each of said hinge members at their outer ends being of oval formation as indicated at 4. The inner ends of hinge member 1 and of the angle extension 3 of hinge member 2 are formed with interengaging portions 5 adapted to receive the pintle 6 whereby said hinge members are pivotally connected together. The hinge member thus formed is of rich and striking appearance especially attractive to the eye of the observer.

I claim:

The ornamental design for a hinge for refrigerators substantially as shown and described.

In testimony whereof I affix my signature in presence of two witnesses.

HARRY C. LEONARD.
